UNITED STATES PATENT OFFICE.

FRED MITCHELL LAWSON, OF CAMBRIDGE, MASSACHUSETTS.

UPRIGHT-PIANO ACTION.

SPECIFICATION forming part of Letters Patent No. 350,006, dated September 28, 1886.

Application filed April 19, 1886. Serial No. 199,354. (No model.)

To all whom it may concern:

Be it known that I, FRED MITCHELL LAWSON, of Cambridge, in the county of Middlesex, of the Commonwealth of Massachusetts, have invented a new and useful Improvement 5 in Upright-Piano-Forte Actions; and I do hereby declare the same to be described in the following specification, and represented in the accompanying drawing, which is a side elevation of a key and its action provided with my invention, the nature of which is defined in the claim hereinafter presented.

In such drawing, A denotes the key; B, the hammer; C, the jack; D, the jack-supporting lever, and E the said jack-lever elevated. The lever D extends under and is fulcrumed to a stationary bar or rail, F, in front of which is a movable bar or rail, G, to which the hammer is hinged. The said bar G projects from the lower arm of a lever, H, to whose upper arm the back-rest I of the hammer is fixed. The fulcrum of the lever H is represented at a. The string is shown at J, and its damper at K, such damper being fulcrumed to the bar F, and has a back-stop, L, as represented. A pin, b, extending upward from and fastened on the rear arm of the jack-supporting lever D, is carried against the tail of the damper during an upward vertical movement of the jack-supporting lever and throws the damper off the string. The back-catch of the hammer is shown at M as supported by a wire, b', projecting upward from the front arm of the jack-lever D. To another wire, c, extending upward from such front arm, and to the tail-block d of the hammer, the hammer-retractor e is fastened. The tripping-button of the jack is shown at f as having its shank g screwed through a bar or rail, h, supported by a bent arm, i, projecting, as represented, from a rock-shaft, k, journaled at one end in a stationary strut, m. From this rock-shaft a stiff wire, n, extends upward through a slide, o, arranged to move on the wire lengthwise thereof and held thereto by a set-screw, p, screwed into the said slide and against the wire. To this slide and the upper arm of the lever H a connecting-rod, r, is jointed, the same being to cause the lever H, while being moved, to advance the hammer and its back-rest toward the string to turn the rock-shaft, so as to depress

the tripping-button, f, nearer to the shorter arm or projection s of the jack.

Before my invention it has been customary, by means of a pedal, to move the hammer and its back-rest toward the string, in order to produce a short movement of the hammer by the key. This, however, carried the jack so far below the tail-block of the hammer as to require a considerable movement of the key 60 before the jack could be forced up to the said block. This rendered rapid movements of the hammer by the key more or less difficult; but with my improvements the hammer-rail is movable with the hammer and its back-rest, 65 the said hammer-rail, while the back-rest is advancing, being moved in a direction away from the rail or bar, to which the damper and jack-supporting lever are hinged. The fulcrum of the lever that carries the back-rest and 70 the hammer-rail is on a level or in line with the jack-bearing of the hammer. Consequently while the hammer and its back-rest are moved forward toward the string, the said bearing or part of the tail of the hammer, 75 against which the upper end of the jack works maintains its position, notwithstanding the hammer-sustaining rail is at the same time in movement away from the damper and jack-lever rail. While the back-rest and hammer 80 are being moved forward toward the string, the jack-operating button-supporting rail is being depressed toward the part s of the jack that is directly under it, from which it will be seen that very little movement of the key will 85 suffice to vibrate the hammer rapidly to the string. Therefore, with my invention, a performer does not have to move a key nearly so far to effect a movement of the hammer to the string when the hammer and its back-rest are 90 in an advanced position, as would be the case were the hammer pivoted to a stationary rail as heretofore.

With my improvement the jack maintains its position relatively to the tail-block of the 95 hammer, whatever may be the distance of the hammer from the string, and thus in depressing the key the performer has the jack close up to the tail-block, and does not have to force the jack upward a distance, in order for it to 100 act on the tail-block.

I claim—

The back-rest I and the hammer-supporting rail G, arranged with and fastened to opposite arms of a lever, H, as set forth, having its fulcrum level or essentially in line with the jack-bearings of the hammers, in combination with the jack-button-supporting rail h, having mechanism, substantially as described, for moving it downward toward the jack during the advance of the back-rest of the hammer, such

mechanism being the rock-shaft k, bent arm i, wire n, adjustable slide o, and the rod r, connecting such slide with the upper arm of the back-rest lever H, all being essentially as represented.

FRED MITCHELL LAWSON.
